JOHN F. HAVEMEYER, OF ARDSLEY-ON-HUDSON, NEW YORK.

REINFORCING-BAR FOR CONCRETE.

1,169,811.

Specification of Letters Patent. Patented Feb. 1, 1916.

Application filed October 9, 1914. Serial No. 865,781.

To all whom it may concern:

Be it known that I, JOHN F. HAVEMEYER, a citizen of the United States, and a resident of Ardsley-on-Hudson, in the county of Westchester and State of New York, have invented an Improvement in Reinforcing-Bars for Concrete, of which the following description, in connection with the accompanying drawings, is a specification, like letters on the drawings representing like parts.

The present invention relates to an improvement in reinforcing bars for concrete construction, one object being to provide a deformed bar which may readily be bent to conform to curved portions of a structure.

In the drawings which accompany this specification I have illustrated several forms of bars embodying my invention.

Fig. 1 is a plan view of such a bar. Fig. 2 a cross section on the line 2—2 of Fig. 1, and Fig. 3 is a plan view of a modification.

Referring now to Figs. 1 and 2, the flat bar there illustrated has a deformed portion on its flat faces, the deformations comprising a series of projections 1 rising from a normally plane surface 2. A continuous track or ridge 3 also rises above the normal surface 2 at each side thereof and extends longitudinally of the bar, and at a height equal to or greater than the height of the projections 1.

While the bar forming the subject matter of the present invention may be used on any type of reinforced concrete work, it is particularly adapted for reinforcing curved structures. In bending reinforcing steel for use on such structures, it is customary to pass the bars through a series of bending rollers to give them the desired curve. However, in passing deformed or irregularly shaped bars through the bending rollers, considerable difficulty has been experienced on account of the projections or deformations which choke the rollers, not only injuring the latter but also tending to flatten out the deformations on the bars.

Referring to Fig. 2 of the drawings, it will be clear that a bar formed according to the present invention, in passing through a set of bending rollers, will engage the surface of these rollers with a bearing surface as provided by the tracks or ridges 3, while the deformations 1 do not necessarily come into actual contact with the rolls. Thus a

bar can be bent easily both without pounding and without damage either to itself or to the bending machinery. The shape of the ridge is not material nor is it necessary that there be any specified number on the face of any bar. While the ridges provide a suitable surface upon which the bending rollers may operate, the deformed portion of the bar with its projections rising from the surface thereof in a slight gradual curve will offer, in actual use, an irregularly shaped surface well adapted to afford the bar a strong anchorage in the concrete.

In Fig. 1, the deformations are shown as extending longitudinally of the bar and separated from each other by the surface thereof, the ends of one projection overlapping the adjacent ends of each two opposite projections. With the deformations running longitudinally as in the figure just mentioned, or substantially so as in Fig. 3, and overlapping each other, a practically constant cross section is produced and the projections enter directly into the tensile strength of the bar. It may be pointed out that, if these projections were directed cross-wise of the bar they might constitute an effective mechanical bond but would not enter materially in the tensile strength of the bar. According to my invention, however, not only is an effective bond provided by the substantially longitudinal projections but these projections also contribute materially in the tensile strength of the bar. Aside from the additional strength given to a reinforcing bar by virtue of the longitudinally disposed projection, this particular placing of the projections simplifies the rolling of such bars considerably. It has been found that this type of bar with longitudinal projections may be readily rolled in a high speed mill and the rolls so used may be easily dressed when they become worn. The projections in the present case are illustrated as being oblong or lozenge shaped and preferably disposed in the manner hereinabove described although it is obvious that the shape of the projections and their relative positions need not be so limited to produce a bar within the concept of my invention.

Among other advantages of reinforcing steel fashioned in accordance with my invention, it may be pointed out that such bars may conveniently be used in reinforcing concrete beams or other parts of a structure to

supplement bars of any well-known cross sectional shape. Moreover, in the construction of silos, sewers, grain elevators and similar structures having curved portions, the comparatively extensive lap or joint ordinarily made at the intersection of two flat or undeformed bars can be substantially shortened where deformed bars are used and consequently the weight of metal necessary in a given structure is materially decreased. Thus, a reinforcing bar made in accordance with a preferred form of my invention provides a reinforcing element of superior strength and at the same time makes possible a substantial economy over the use of plain flat bars which have heretofore been largely employed in reinforcing curved structures.

I claim as my invention:

1. A relatively flat reinforcing bar substantially rectangular in cross section and having a pair of straight longitudinally extending ridges and a plurality of relatively small deformations, separate from each other and from the ridges, on at least one of its broader faces, the ridges being of uniform

height and extending above the tops of the deformations, whereby the bar may be passed smoothly between bending rollers and be bent without interfering with the deformations.

2. A relatively flat reinforcing bar substantially rectangular in cross section and having a pair of longitudinally extending ridges on each of its two broader faces and a plurality of relatively small separate deformations between each pair of ridges and arranged relatively to each other to preserve a uniform cross sectional area throughout the bar, the ridges being of uniform height, whereby the bar may be passed smoothly between bending rollers and be bent without interfering with the deformations.

In testimony whereof, I have signed my name to this specification, in the presence of two subscribing witnesses, this 6th day of October, 1914.

JOHN F. HAVEMEYER.
